(57) **CLAIM**

The ornamental design for an information storage media holder with security feature, as shown and described.

DESCRIPTION

This application claims priority based on U.S. Application Ser. No. 29/142,204, now allowed, which in turn claims priority from U.K. Design Patent Applications GB 2097611, filed Nov. 22, 2000; GB 2097612, filed Nov. 22, 2000; GB 2097613, Nov. 22, 2000; and GB 2097614 filed Nov. 22, 2000. The entire disclosure of each of these prior-filed applications is hereby incorporated herein by reference.

FIG. 1 is a top plan view of an information storage media holder with security feature showing my new design;

FIG. 2 is a front elevation view thereof; and,

FIG. 3 is a top perspective view thereof.
